UNITED STATES PATENT OFFICE.

RUDOLPH BECKER, OF PLAINFIELD, NEW JERSEY, ASSIGNOR TO THE SINGER MANUFACTURING COMPANY, OF ELIZABETH, NEW JERSEY, A CORPORATION OF NEW JERSEY.

THREAD-CONTROLLING MECHANISM FOR SEWING MACHINES.

Application filed February 4, 1926. Serial No. 85,842.

This invention relates to thread-controlling mechanism for sewing machines and has for an object to improve the mechanism disclosed in my Patent No. 1,386,307, of August 5 2, 1921. In the mechanism disclosed in said patent there is embodied a thread-nipper device comprising an adjustable nipper-seat connected to the feed-adjusting means, and a nipper-head which is actuated by means of 10 an eccentric on the main-shaft. With this device, an adjustment of the feed or stitch-length alters the timing of both the beginning and ending of the nip, whereas for best results the timing of the ending of the nip 15 should be the same for all stitch lengths, for at this time the eyed and hooked needles are emerging from the upper side of the work and the thread should be allowed to run freely from the supply as the needles move to 20 the upper limit of their stroke. It has been proposed (see U. S. Patent No. 392,087) to utilize a barrel cam for actuating the thread-nipper, said cam having a ledge or step parallel to its axis to effect the release of the 25 thread at a fixed time and an obliquely or spirally formed let-off portion to effect the nipping of the thread at a time dependent upon the stitch-length adjustment, such adjustment effecting a shift of the cam length- 30 wise of the cam's axis so that the let-off portion will be engaged earlier or later by the cam-follower. A cam mechanism of this character is, however, rather bulky and complicated and requires considerable space 35 within the machine for its installation and operation.

An object of the present invention is to provide a nipper-operating mechanism of compact and simplified construction retaining 40 the desirable characteristics of a variable beginning and a fixed ending of the time of the nipping action.

A further object of the invention is to provide for proper tensioning of the thread 45 when sewing with stitches of short or medium length while permitting the thread to run more freely when sewing longer stitches.

To this end there is provided a thread-nipper having co-acting members one of which 50 (the nipper-seat) is adjustable and the other of which (the nipper-head) is connected to a cam-follower cooperatively related to a cam fixed on the machine shaft and formed with a graduated eccentric let-off portion al-

lowing the nipper-head to approach the nipper-seat over a certain portion or fraction of the stitch-forming cycle; the time at which the nip actually occurs depending upon the position of adjustment of the seat toward or away from the nipper-head. The cam also is formed with an abrupt cam-rise following the graduated eccentric or let-off portion and equal to the total drop of such let-off portion to effect the release of the thread at a fixed period of the stitch-forming cycle for all stitch-lengths at about the time when the eye of the eyed needle is doubling its thread through the work.

A thread tension device is also used in addition to the thread-nipper and the adjusting means for varying the timing of the thread-nipper is connected to open the tension device when the nipper is adjusted for sewing long stitches.

In the accompanying drawing, Fig. 1 is 75 a side elevation of a sewing machine embodying the invention. Fig. 2 is a horizontal section through the bracket-arm standard of the machine, showing the bed in plan. Fig. 3 is a front end elevation of the machine bed. Fig. 4 is a sectional view on the line 4—4, Fig. 2. Fig. 5 is a sectional view on the line 5—5, Fig. 1. Fig. 6 is an inside elevation of the nipper-adjusting lever and Figs. 7, 8 and 9 are, respectively, diagrammatic views illustrating the variation in the timing of the beginning point of the nip for short, intermediate and long stitches.

The invention is disclosed as embodied in a straw-braid sewing machine having the 90 usual eye-pointed needle 1 and hook needle 2 actuated by suitable mechanism such as that disclosed in my Patent No. 1,429,399, of Sept. 19, 1922, which also discloses a suitable form of presser-foot and looper mechanism. The feeding mechanism comprises a feed-dog 3 which is carried by the feed-bar 4 fulcrumed at 5 on the feed-rocker 6. Rising and falling movements are imparted to the feed-bar by means of the feed-lift eccentric 7 on the main-shaft 8. The feed-lift eccentric actuates the pitman 9 which raises and lowers the support 10 for the link 11 pivoted at 12 to the feed-bar 4; this mechanism being constructed substantially in accordance with the disclosure of my said patent. Feed-and-return movements are imparted to the feed-rocker 6 by means of the

forked pitman 13 which embraces the cam 14 on the main-shaft and has a link connection 15 with an arm 16 on the feed-adjusting lever which is fulcrumed at 17; the other arm 18 5 of the feed-adjusting lever projecting exteriorly of the machine bed and carrying a spring-pressed latch-member 19 having a toothed end 20 adapted to engage a selected one of a series of depressions in the stationary rack-member 22. Fulcrumed at 23 on the head 18' of the lever-arm 18 is a lever 24 having a cam edge 25 which forces the latch-member 19 outwardly to disengage the tooth 20 from the rack 22 preliminary to swinging 15 the lever 18 for adjustment of the stitch-length.

An under-thread take-up lever 26 is fulcrumed at 27 on the machine frame and is formed at its free end with a thread-eye 28. 20 This lever 26 is actuated by means of the link-connection 29 with the pitman 9.

The machine is provided with a thread-controlling device including spaced thread-eyes 30 between which plays the apertured 25 end 31 of a thread-controlling lever 32 fulcrumed on the main-shaft 8 and having its rearwardly extending arm 33 formed with an arcuate cam-slot 34 which is engaged by a pin 35 secured to the pitman 13 by the 30 screw-and-slot adjustable fastening 36 permitting adjustment of the pin 35 longitudinally of the guideway 37 on the pitman 13.

The intermittent thread-nipping device comprises coacting nipper-seat and nipper-head members 38 and 39, respectively. The 35 nipper-seat member 38 is an apertured cylindrical member which is fixed within the cylindrical casing 40 rotatably and slidably fitted to an aperture in the frame wall 41 40 of the machine bed. The member 40, Fig. 2, has an inclined slot 42 cut in its wall and this slot is entered by a screw 43 whereby a turning movement imparted to the casing 40 will cause such casing and the nipper-seat 45 38 to move in and out in an axial direction or toward and away from the nipper-head 39.

The casing 40 has fixed thereto, Fig. 6, the lever 44, one arm of which is forked 50 at 45 to embrace the feed-adjusting lever arm 18. The other arm of the lever 44 has an inclined end 46 serving as a releasing cam for the tension device 47. Referring to Fig. 5 it will be observed that the constant or 55 non-intermittent tension device includes the usual thread-engaging disks 48 and adjustable tension spring 49 the pressure of which on the disks may be entirely relieved by an outward thrust on the tension-releasing pin 60 50; such thrust being caused by the cam end 46 of the lever 44 when the feed-adjusting mechanism is adjusted to sew long stitches.

The nipper-head 39, Fig. 4, is carried by a shank 51 passing axially through the cylindrical nipper-seat and having secured to 65

its inner end the cam-follower roll 52. A spring 53 housed within the nipper-seat cylinder 38 tends to draw the head 39 into effective nipping relation with the seat 38.

To hold the nipper open and permit it 70 to close at predetermined intervals of a stitch-forming cycle there is fixed to the main-shaft 8 a cam 54 having an abrupt nipper opening incline 55 followed by a concentric portion to the beginning point 56 75 of a graduated eccentric let-off portion ending at 57, such let-off portion extending over some 120° or more of the cam's extent, as shown by the dotted radial lines, Fig. 4. It will be observed that in the embodiment 80 illustrated the let-off portion embraced within the radial dotted lines is graduated into three let-off steps 56^a, 56^b and 56^c, i. e., is a stepped eccentric curve, and it has been found that a sufficiently accurate timing of 85 the closure of the nipper for all stitch-length adjustments is produced by a three-step graduated nipper-closing cam-portion.

Referring to Fig. 7, the feed being adjusted for short stitches, the nipper-seat occupies a position so near to the nipper-head 90 39 that the let-off portion 56^a of the cam permits the nipper-head to nip the thread against the nipper-seat as the needles are nearing the end of their down stroke. With 95 a short stitch the thread is slack at this time and the subsequent action of the take-up 26 and thread-controller 32 controls the slack-thread until the rising eye-pointed needle has safely entered the loop carried 100 by the hook-needle.

When sewing stitches of intermediate length, Fig. 8, the time of the nip should be delayed to permit more thread to be drawn into the stitch and such delay is effected by 105 virtue of the intermediate positioning of the nipper-seat by its connection with the feed-adjusting mechanism. When the nipper-seat occupies intermediate position it is not near enough to the nipper-head to nip the thread when the roller 52 rides on the first let-off step 56^a but does nip the thread when the roller rides onto the second let-off step 56^b. After the thread is nipped, the downwardly moving take-up 26 holds the thread-loop snugly in the barb of the rising hook needle until the eye-pointed needle has 110 safely entered such loop.

When sewing long stitches, Fig. 9, the nip is delayed until the needles are entering the 120 work. The long stitch-adjustment of the feed, shifts the nipper-seat so far away from the nipper-head that the two do not come into effective nipping relationship until the roller rides onto the third let-off step 56^c. It will be seen that the present variably 125 timed nipper mechanism is of compact and simple construction and requires but little space within the machine bed for its installation.

Having thus set forth the nature of the invention, what I claim herein is:—

1. In a thread-nipper mechanism for sewing machines, the combination with coacting thread-nipping members, one of which is active and the other of which is adjustable toward and away from the active member, of an operating cam for actuating the active nipper member having a graduated eccentric nipper-closing portion and an abrupt nipper-opening portion.

2. In a thread-nipper mechanism for sewing machines, the combination with a nipper-head and a nipper-seat adjustable toward and away from the nipper-head, of a nipper-head operating cam having a graduated eccentric nipper-closing portion followed by an abrupt nipper-opening step substantially equal to the total drop of said graduated nipper-closing portion.

3. In a thread-nipper mechanism, a frame-support, a shaft, a nipper-operating cam fixed to said shaft, a cylindrical nipper-seat mounted in said frame for axial adjustment transversely of said shaft, a nipper-head opposed to said seat, a shank carrying said nipper-head and passing through said seat, a cam-follower carried by said shank in cooperative relation with said cam, said cam having a graduated eccentric let-off portion followed by an abrupt nipper-opening step substantially equal to the total drop of said let-off portion.

4. In a sewing machine, the combination with feed-adjusting mechanism, of a thread-nipping device including coacting nipping elements, means connected to the feed-adjusting mechanism for shifting one of said elements toward or away from the other, and means for actuating the other nipping element, said means including a cam having a radially graduated nipper-closing portion followed by an abrupt nipper-opening portion.

5. In a straw sewing machine, the combination with stitch forming mechanism including side-by-side eye and hook needles and feed-adjusting mechanism, of a constant tension device, and means connected to the feed-adjusting mechanism for entirely opening the tension device when the feed-adjusting mechanism is set for the production of the longer stitches.

6. In a sewing machine, the combination with feed-adjusting mechanism, of an intermittent thread-nipping device and a constant tension device, and means connected to the feed-adjusting mechanism for varying the time of action of the thread-nipping device in accordance with the stitch-length adjustment and for opening the tension device for a long-stitch adjustment.

In testimony whereof, I have signed my name to this specification.

RUDOLPH BECKER.
